GESELLSCHAFT, OF STUTTGART, GERMANY

IGNITION DEVICE FOR AIRCRAFT ENGINES

Application filed July 13, 1931, Serial No. 550,535, and in Germany October 7, 1930. Renewed
July 19, 1932.

The present invention relates to a battery ignition device more particularly for aircraft engines.

The object of the invention is to obtain satisfactory ignition under all working conditions by using devices which are to be kept as simple as possible and eliminate sensitive constructions which can be the causes of unsatisfactory working.

10 As is known, with aircraft there are only two definite working conditions, idle running and running on full load. As a rule, therefore there are two adjustments of the ignition device, these being a predetermined advanced ignition position and a predetermined retarded ignition position. It is known to combine two make and break devices with these two adjustments one being permanently adjusted to advanced ignition 15 and the other permanently adjusted to retarded ignition, these being connected into the primary circuit as required.

On the other hand, with full load, large spark gaps are as is known used for aircraft engines. In order to obtain this, it is known to vary the resistance connected into the circuit in front of the ignition coil, automatically by governors working in dependence upon the speed of rotation, as well as to alter 20 the closed or condenser charging period by using two make and break devices which are connected in parallel and can be mutually adjusted by a certain amount. These regulating or governing devices harbour a source 25 of trouble in themselves because they are very dependent upon the lubrication, bearing and property of contacts of the governor and the like.

On the basis of the knowledge that there 30 is no need for any regulating steps or degrees between idle running and loaded running, these disadvantages can be eliminated according to the invention with aircraft battery ignition in that mechanisms are provided which influence the capacity of the sparks in such a way that they are not harmfully large at the retarded ignition position but are adequate at the advanced ignition position.

50 In one form of construction a constant re-

sistance is connected in front of the retarded ignition make and break device which is greater ohmic resistance than that in front of the advanced ignition make and break device. In this way the ignition system can be simplified as is very desirable in aircraft construction, by constructing the leads to the make and break devices themselves as resistances. In addition the closed or "make" period of the advanced ignition make and 55 break device can be made permanently greater than that of the retarded ignition make and break device in order to help the two different resistances in their endeavour to obtain a strong spark at high speed of rotation. In addition to the procedure already mentioned, the known change in induction of the coil can be utilized, the operation of which is preferably positively combined with the reversal of retarded to advanced ignition.

Various forms of construction of the invention are shown in the drawing in which:

Figure 1 shows a battery ignition device with advanced and retarded ignition make 75 and break devices in each circuit of which a special resistance is inserted.

Figure 2 shows a battery ignition device having two make and break devices and a separate cam for each make and break device, the 80 closed or "make" period of which is made relatively different.

Figure 3 shows the same arrangement as Figure 2 in which the induction of the ignition coil can be varied in addition.

In Figure 1 one end of the low tension winding 1 of the ignition coil is connected to one pole of the battery 3, the other pole of which is earthed. One end of the high tension coil 2 is also earthed, whilst the other is led through the distributor 4 to the sparking plugs 5. The end of the coil 1 which is not connected to the battery is connected to the pivotal point 6 of a switch arm of the switch A which can contact with any of the three contacts 7, 8 and 9. Of these, 7 is an idle contact and 8 is connected to the insulated make and break arm 12 of the make and break device of the ignition coil through a series resistance 10. This ignition coil has two make 95 100

and break devices having the insulated arms 12 and 13, and the corresponding stationary contacts 14, 15 which are earthed. The make and break device arms 12 and 13 are moved by the rotating cam 14 which is driven in timed relation by the engine. The arm 13 is connected to the contact 9 of the switch A through the intermediary of a resistance 11. The essential feature of the connection is that the resistances are constant and that the resistance 10 lying in the advanced ignition circuit is smaller than the resistance 11 lying in the retarded ignition circuit.

The wiring and arrangement according to Figure 2 is the same as in Figure 1 with the exception of the make and break device.

In order to obtain different breaking or interruption periods for the advanced ignition make and break and the retarded ignition make and break a separate rotating cam is provided for each make and break circuit. The arm 12 is operated by the cam 17 and the make and break device arm 13 is operated by the cam 18. The two cams are mounted on the same shaft and are so mutually displaced that when the cam shaft rotates in clockwise direction, first the arm 12 is raised and then the arm 13 is raised actually so much later as the angle line a_1-a_1 pursues the angle line a_2-a_2 . In addition the two cams are constructed differently. Different breaking or interruption times correspond to the angle 1 and 2 at the same velocity of rotation. As long as the cam follower 19 of the arm 12 is within range of the angle α^1 , which in the example shown occurs four times in one revolution of the cam and the cam follower 20 of the arm 13 is within range of the angle α^2 , the arms are lifted, that is to say the corresponding circuits are broken. As the angle α^2 of the retarded ignition make and break device is greater than the angle α^1 of the advanced ignition make and break device the making or closed period of the advanced ignition make and break device is also greater than that of the retarded ignition make and break device. This different form of construction of the make and break device increases the action which it is endeavoured to obtain through the series resistance.

In Figure 3 the low tension coil 1 is tapped at a place 25 so that the induction of the coil may be changed. The end of the coil 1 is led to the contact 24 of the switch B instead of directly to the terminal 8 and the tapping at 25 is connected to the contact 23 of the switch B. The contact arm of the switch B which is rotatable about 21 is positively coupled to the arm of the switch A. The pivotal point 21 is connected to the pivotal point 6 of the contact arm of the switch A; the remainder of the connection is as shown in the wiring diagram of Figure 2.

The method of operation of the various modifications is shortly explained as below:—

If in Figure 1 the contact arm of the switch A is connected to the contact 9 the current passes from the battery through the coil 1, the switch A and the series resistance 11 to the retarded ignition make and break device 13, 15. The series resistance is chosen of such magnitude that the coil 1 and the make and break device contact place 15 are not overstrained. For advanced ignition it is reversed from contact 9 to contact 8: the current now passes through the series resistance 11 which is smaller than the resistance 10 so that a spark, which is capable of ignition, is even formed at high velocity.

The arrangement in Figure 2 only differs from the arrangement in Figure 1 in that the retarded ignition make and break device has a shorter closed or making period than the advanced make and break device.

If the switch A is connected to the contact 9, that is to say, to retarded ignition, the resistance 11 and also a comparatively short closing or making period of the make and break device 13 prevent the coil 1 and the make and break contacts being too heavily loaded and more particularly the battery 3 being discharged to an unnecessarily high degree, even when the motor is running at a low speed of rotation. On the other hand with the connection to advanced ignition a good spark is produced by the resistance 10 which is small compared with the resistance 11, and a comparatively long making or closing period of the make and break device 12 even at a high speed of rotation.

In the arrangement shown in Figure 3 the induction of the coil 1 is changed in addition and actually in dependence upon the adjustment of the ignition timing. On that account the two contact arms of the switches A and B are mechanically connected to each other. If, for example, the switch A is in the retarded ignition position that is to say on the contact 9, the switch B is positively at rest on the contact 24. The current accordingly passes through the entire coil 1 through the switch B, the switch A and the resistance 11 to the make and break device. The electrical and magnetic conditions are the same as in the arrangement of Figure 2. With the advanced ignition position of the switch A on the contact 8, the switch 13 is at rest on the contact 23. The current now only passes through one portion of the coil 1 and then through the switches B and A and through the resistance 10 to the make and break device 12. The magnetic time constant of the coil has become smaller through the reduction in the number of windings and as a result the increase in current greater at a given voltage which is very desirable in view of the actual short making or closing periods at high speeds of rotation.

For starting the aircraft motor a buzzer ignition is connected in known manner to the

retarded ignition make and break device which feeds the current of a special ignition coil to a starting electrode of the distributor.

The great advantage obtained by the invention lies in the first case in the simplicity and absolute reliable operation of the arrangements. The fly wheel governor for regulating the series resistance, the contact path for the resistance and a rotating governor for the adjustment of the ignition timing previously used are eliminated as devices which are liable to become worn out, which are sources of failure and which require attention. A further advantage is the cheapening of the ignition device and the reduction in weight thereof which is very desirable in aircraft where a reserve ignition system is provided for each engine.

I declare, that what I claim is:

1. An ignition device for aircraft engines comprising a battery, an induction coil connected to said battery, a make and break device set in the retarded ignition position, a second make and break device set in the advanced ignition position, a change-over switch, connected to said ignition coil, a resistance connected in series between said first make and break device and one pole of the switch and a second resistance of less ohmic resistance connected in series between said second make and break device and the other pole of the switch.

2. An ignition device for aircraft engines comprising a battery, an induction coil connected to said battery, a cam, an interrupter contact set in the advanced ignition position in relation to said cam and operated thereby, a second interrupter contact, a second interrupter cam set in the retarded ignition position with relation to said cam, a change-over switch connected to said induction coil and having a pair of contacts, a resistance connected in series between one of said switch contacts and the first interrupter contact and a second resistance of greater ohmic resistance than the first resistance connected in series between the other switch contact and the second interrupter contact.

3. An ignition device for aircraft engines comprising a battery, an induction coil connected to said battery, a cam, an interrupter contact operated by said cam and set in the advanced ignition position, a second cam having a shorter low portion than the first cam, a second interrupter contact set in the retarded ignition position and operated by said second cam and a change-over switch connected to said induction coil and having a pair of contacts, a resistance connected in series between one of said switch contacts and the first interrupter contact and a second resistance of greater ohmic resistance than the first resistance connected in series between the other switch contact and the second interrupter contact.

4. An ignition device for aircraft engines comprising a battery, an induction coil connected to said battery and having a tapping thereon, a cam, an interrupter contact operated by said cam and set in the advanced ignition position, a second cam having a shorter low portion than the first cam, a second interrupter contact set in the retarded ignition position and operated by said second cam, a resistance in series with the first interrupter contact, a resistance of greater ohmic resistance in series with said second interrupter contact and means to alternatively connect said second interrupter contact with the induction coil and the first interrupter contact with the said tapping.

5. An ignition device for internal combustion engines comprising a circuit including a source of current, an induction coil, a make and break device set in the retarded ignition position, a second make and break device set in the advanced ignition position, and switch means for connecting either of said make and break devices in said circuit, the resistance of the circuit through said first mentioned make and break device being greater than that through the second make and break device.

6. An ignition device for internal combustion engines comprising a circuit including a source of current, an induction coil, a make and break device set in the retarded ignition position, a second make and break device set in the advanced ignition position, and switch means for connecting either of said make and break devices in said circuit, the closed period of the make and break device set in the advanced ignition position being greater than that of the other make and break device.

7. An ignition device for internal combustion engines comprising a circuit including a source of current, an induction coil, a make and break device set in the retarded ignition position, a second make and break device set in the advanced ignition position, and switch means for connecting either of said make and break devices in said circuit, the resistance of the circuit through said first-mentioned make and break device being greater than that through the second make and break device and the closed period of the second make and break device being greater than that of the first make and break device.

8. An ignition device for internal combustion engines comprising a circuit including a source of current, an induction coil, a make and break device set in the retarded ignition position, a second make and break device set in the advanced ignition position, switch means for connecting either of said make and break devices in said circuit, and means for short circuiting a portion of the primary of said induction coil when the second make and break device is connected in circuit.

9. An ignition device for internal combustion engines comprising a circuit including a source of current, an induction coil, a make and break device set in the retarded ignition position, a second make and break device set in the advanced ignition position, switch means for connecting either of said make and break devices in said circuit, the resistance of the circuit through said first mentioned make and break device being greater than that through the second make and break device, and means for short circuiting a portion of the primary of said induction coil when the second make and break device is connected in circuit.
10. An ignition device for internal combustion engines comprising a circuit including a source of current, an induction coil, a make and break device set in the retarded ignition position, a second make and break device set in the advanced ignition position, switch means for connecting either of said make and break devices in said circuit, the resistance of the circuit through said first mentioned make and break device being greater than that through the second make and break device and the closed period of the second make and break device being greater than that of the first make and break device, and means for short circuiting a portion of the primary of said induction coil when the second make and break device is connected in circuit.
11. An ignition device especially for aircraft engines comprising a source of current, an induction coil connected to said source, a make and break device set in the retarded ignition position, a second make and break device set in the advanced ignition position, and means, including switch means to connect said make and break devices with said induction coil, to vary the primary current of said induction coil so that at retarded ignition position the current is not harmfully large and at advanced ignition position it is large enough to produce a sufficient spark.
- In testimony whereof I hereunto affixed my signature.

ERICH KLAIBER.
